[57] **CLAIM**

The ornamental design for a squirrel feeder, as shown and described.

DESCRIPTION

FIG. 1 is a perspective view of a squirrel feeder showing my new design;

FIG. 2 is a left side elevational view thereof, the right side being a mirror image of the left side shown;

FIG. 3 is a top plan view thereof;

FIG. 4 is a front elevational view thereof, the rear being plain and unornamented; and,

FIG. 5 is a bottom plan view thereof.

FIG. 1

FIG. 2
